United States Patent Office.

IMPROVEMENT IN DUMPING WAGONS.

J. L. ORDNER, OF CLEVELAND, OHIO.

Letters Patent No. 60,413, dated December 11, 1866.

The Schedule referred to in these Letters Patent and making part of the same.

TO ALL WHOM IT MAY CONCERN:

Be it known that I, J. L. ORDNER, of Cleveland, in the county of Cuyahoga, and State of Ohio, have invented certain new and useful Improvements in Dumping Wagons; and I do hereby declare that the following is a full and complete description of the construction and operations of the same, reference being had to the accompanying drawings, making a part of this specification, in which—

Figure 1 is a perspective view of the wagon box, with my improvement, detached from the wheels.

Figure 2 is a top view with the box removed.

Figure 3 is an end view of fig. 1.

Like letters of reference refer to like parts in the several views.

My improvement relates to dumping wagons as hereinafter described. A represents a wagon box, of any suitable form or construction, placed on a frame F. This frame is supported on bolsters, G, between which are longitudinal pieces h. The frame F consists of side pieces f, with cross pieces f' extending between and secured to them. In the side pieces are arranged rollers e in slots e', the shafts of which have their bearings in a suitable manner in the frame. These rollers project a little above the top of the frame, so that the box A, when it is placed on, rests upon them. The outer side of the side pieces extends up, forming guides e, on each side of the box. The frame F is held firmly in place, on the bolsters, by means of stakes h' secured in the bolster, that are fitted into the side pieces as represented. The box A is placed on the frame between the guides e, resting on the rollers e. The rollers are metal, and there is a metal strip i on each side of the box where it rests, and runs on the rollers. The box is held stationary on the rollers by means of a fastening N, that consists of a strap m connected to an eye, or staple j, in one of the bolsters, and is placed at the other end on an eye n, secured in the under side of the box. After the strap is adjusted on the eye n, by means of the slot o, a hook n' on the end of a chain m' is inserted in the eye n, thereby holding the strap up in place. The chain is attached to the end of the frame F. By this adjustable fastening the box is prevented from moving on the rollers until it is desired to empty it, when the hook is removed from the eye n, and the strap let down. The box is then run along on the rollers and tipped down, when the end can be slipped out, and the load readily discharged. The great advantages of this arrangement are, that the box, however heavily loaded, can easily be run along and tipped up into the position for discharging the load, and readily adjusted into place again, the rollers overcoming the friction; and the wagon box can be supported on four wheels in place of two, so that the box can be larger and of a more appropriate shape for carrying loads. And a much heavier load can be carried in this than the ordinary dumping cart, for the strain and weight of the load rest more upon the wheels and not so much upon the horse, so that the horse can draw a heavier load with the same ease. It is also more easily dumped for discharging the load. A tongue can be connected to this wagon, and two horses attached if desired.

What I claim as my improvement, and desire to secure by Letters Patent is—

The rollers e and frame F, when constructed and arranged in relation to each other, as set forth, in combination with the described box A, provided with fastenings, N, the whole supported upon the bolsters G, when used conjointly in the manner and for the purpose set forth.

J. L. ORDNER.
